UNITED STATES PATENT OFFICE.

MAX PAUL ERNST HOHN, OF DRESDEN, GERMANY, ASSIGNOR TO "UNIVERSELLE"
CIGARETTENMASCHINEN-FABRIK J. C. MÜLLER & CO., OF DRESDEN, GERMANY.

CIGARETTE CUTTER.

Application filed June 10, 1920. Serial No. 388,081.

To all whom it may concern:

Be it known that I, MAX PAUL ERNST HOHN, residing at Dresden-A., Zwickauer strasse 48, Germany, have invented certain new and useful Improvements in Cigarette Cutters, of which the following is a specification.

My invention relates to improvements in cigarette cutters of the type referred to hereinbelow and the object of my invention is to provide for an improved construction of the bearings and shafting carrying the cutting blade or blades in which a certain disadvantage connected with the types heretofore in use will be avoided.

I attain my object in view by the construction and arrangement of parts herein-after described and on the drawing herewith illustrated in which Figure 1 is a vertical longitudinal section through a shafting as herein explained, Figure 2 is a transverse vertical section taken through the intermediate portion of the shafting and Figure 3 a horizontal longitudinal section through the same. Figure 4 is a vertical longitudinal section and Figure 5 a vertical transverse section through a shafting showing a specific feature of my improvement as herein-after more particularly set forth.

In cigarette machines the revolving blade which cuts cigarettes of desired length for use from an integral blank roll, previously formed in and fed from a machine, has to be moved forwardly in the direction of the feed of the roll at a rate which corresponds to that of the feed of the roll, if a smooth cut is desired. For this purpose, a rotary shaft has heretofore been provided on a reciprocating sliding carriage permitting a rocking movement of the shaft to move the blade transversely against the blank roll of cigarettes.

As the carriage of the usual machine must carry a heavy and large mass, and as the speed of the carriage accelerates upon each reciprocation thereof, such mass greatly retards the required acceleration. The speed of the blank roll feed is dependent on the rate at which the carriage travels in the direction of the blank roll feed. While this speed is certainly considerable in the machines heretofore in use, whose production amounts already to a daily output of a hundred thousand or more cigarettes, still, a further increase would be of advantage.

This increase is, however, dependent on a quicker reciprocating movement of the cutter and this can, in turn, be attained only by considerably reducing the bulk of the mass to be moved with the cutter.

With a view of removing the disadvantage referred to I provide a type where the shaft carrying the cutter blade or blades is permitted to move forward and back alone, without requiring those parts which cause the rotation and nodding movements of the cutter shaft to join in the said axial movements. This means a considerable reduction of the reciprocating body and permits of a much speedier axial movement of the cutter shaft than could be attained heretofore. The result will be an accelerated feed of the string and a corresponding enlargement of the daily output of cigarettes.

The bearing of the cutter-shaft being an important feature for the uninterrupted rapid forward and return movements I provide for an additional shaft which is hollow and embraces the said cutter shaft, transmitting to the same rotatory movement, but remaining stationary with respect to axial movement, the cutter shaft alone being axially movable within the said hollow outer shaft. For the connection of the two shafts I provide in suitable transverse bores in the hollow shaft catches bearing against longitudinal flattenings provided in the inner or cutter shaft, thus securing rotation and at the same time easy axial movements of the said inner shaft.

The drawings show a cutter shaft *a* carrying at one end a seat for the cutter blade or blades *b*. The said shaft *a* is inserted in another shaft *c* which is hollow and has a box *d*. The said hollow shaft *c* has further a seat *c'* on which a pulley may be mounted to impart rotation, a key *e* being provided in the said hollow shaft for the securement of the hub of the said pulley. The parts *c'* of the hollow shaft are intended for the engagement in suitable bearings not shown on the drawings.

In the inner or cutter shaft *a* there are provided a pair of longitudinal shallow flat recesses or faces *f* while the outer shaft *c* has two parallel transverse slots in which are inserted the aforementioned catches, Figure 2 showing bars or bolts *g* bearing against the said flat faces *f*. Thus the cutter shaft *a* will be caused by the said catches *g* to follow up

the rotation of the outer shaft *c* while the said faces *f* permit of its axial movements to an extent which corresponds to their length.

Various changes in the form and minor details of construction may be resorted to without departing from the spirit and scope of my invention. Thus the aforesaid catches *g* are in Figures 4 and 5 substituted by small rollers *h* rotarily supported by small axes *k*, the said rollers being mounted in transverse recesses *i* in the outer shaft *c* and touch the aforesaid flat faces *f* on which they roll for the axial movement of the shaft *a*.

I am aware that prior to my invention cigarette cutters have been made in which the cutter shaft reciprocates axially in a bearing which does not move in longitudinal direction; but in these machines the slide or carriage is merely separated without any reduction of the bulky mass which has to join in the movements hereinabove referred to.

I claim:—

1. In a cigarette cutter, the combination of a rotatable and axially movable shaft having a longitudinally disposed flat face, a cutter mounted on the shaft, a hollow rotatable shaft mounted on the first shaft, and means on the hollow shaft for engagement with the flat face of the first shaft for inter-

locking the shafts for rotation and permitting axial movement of the first shaft in the hollow shaft.

2. In a cigarette cutter of the type hereinabove referred to the combination of a rotatable and axially movable shaft adapted for attachment thereto of a cutting blade or blades and having longitudinal flat faces, of a rotatable hollow outer shaft in which the body of the said first-mentioned shaft is enclosed, and catches in the said outer shaft adapted to bear against and move on the said flat faces of the said inner shaft.

3. In a cigarette cutter of the type hereinabove referred to, having a rotatable and axially movable shaft adapted for attachment thereto of a cutting blade or blades, and a rotatable outer shaft which is hollow, enclosing the body of the said first mentioned shaft, which first-mentioned shaft has longitudinal flat faces, means in suitable transverse slots in the said outer shaft adapted to bear against and move on the said flat faces.

In testimony whereof I affix my signature in presence of two witnesses.

MAX PAUL ERNST HOHN.
